(57) CLAIM

The ornamental design for a folding crib diaper backpack, as shown and described.

DESCRIPTION

FIG. 1 is a front view of a folding crib diaper backpack showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view of a folding crib diaper backpack showing its cover is open; and,

FIG. 8 is the second perspective view of a folding crib diaper backpack showing its cover is closed.

The broken lines in the figures are for the purposes of illustrating portions of the folding crib diaper backpack, which form no part of the claimed design.
